BIAS BUFF AND METHOD OF MAKING THE SAME

Albin S. Rock, East Bridgewater, Mass., assignor to
F. L. & J. C. Codman Company, Rockland, Mass., a
corporation of Massachusetts

Application April 15, 1955, Serial No. 501,504

7 Claims. (Cl. 51—193)

This invention relates to bias buffs and the object is to provide an improved construction of "section," which in the more usual applications will be set side by side with other sections to form a "wheel" of the desired width of face, and to a novel method of making the same. A "section" however might be used alone and then would be a "wheel" having a narrow face. Whatever the name the "section" is a manufacture as such and may be a separate article of sale. An important advantage to which, however, the invention in its broader aspects is not limited, is that the construction and method permit utilizing short pieces of fabric for forming certain of the plies of the section.

By "bias buff" I refer to a buff made of a number of plies of a woven fabric set on edge and presenting the ends of the yarns diagonally at the working face of the buff. If we took a length of one of these plies, which in the finished article is annularly curved (a circular ring sector), and drew it out in a straight line, it would be a straight strip as cut from a woven fabric on the bias as, indeed, it originally was. In bringing the fabric to annular form the weave may be somewhat distorted and also, the fabric, when considered as a sheet will be compressed into convolution or pleats, in particular near the inner circumference of the annulus and progressively throughout its radial depth. In the case of a so-called "ruffled" buff, the outer circumference is also compressed, the developed length of the fabric being greater than the circumference and the edge portion of the fabric which engages the work is tortuously convoluted.

An obvious way of producing a bias strip which can be brought into annular form is simply to cut it from a web of fabric by two diagonal cuts. If the web is 36 inches wide and cut at a true bias angle of 45 degrees, this will produce a strip about 50 inches long, and such strips can be sewn together end to end to make a longer one. In practice however it has been customary to seam together the selvages of a length of fabric to form a tube and this tube was divided by helical cuts of the proper spacing and at a suitable helix angle to produce strips of indefinite length, which were of short lengths connected together end to end. Such a long strip was usually wound up in a coil like that of a clock spring or a piece of tape on a spool, and when a sufficient number of plies were accumulated the spiral was folded up in the middle to provide two plied annuli. It has also been proposed to cut bias strips from a web and to sew together the ends of each one. A number of these short sleeves were telescoped to provide the desired number of plies, and folded up in the middle. This procedure is subject to various objections and so far as I know has not been generally practiced.

In accordance with the invention a different method of forming the plied annulus is provided leading to a different ultimate construction and having the advantage both as a method and as an article, that one or more of the plies can be formed from short pieces or remnants.

My invention will be well understood by reference to

2

the following description of the preferred embodiment thereof taken in connection with the accompanying illustrative drawings, wherein:

Fig. 1 is a plan view with parts broken away illustrating an initial stage of the assembly of plies of fabric;

Fig. 2 is a similar view showing a later stage of the assembly, parts again being broken away and a part turned back;

Fig. 3 is a plan view of a portion cut from the assemblage;

Fig. 4 is a similar view showing the portion of Fig. 3 folded;

Fig. 5 is an end view which shows how the folded blank of Fig. 4 may be manipulated to facilitate the operation of a sewing machine thereon;

Fig. 6 shows the completed blank after sewing;

Fig. 7 is a perspective which represents the blank opened up to show that its form is an open-ended sleeve;

Fig. 8 is a similar view of a relatively short piece cut from the sleeve, similarly opened up, this piece being adapted to be transformed into an annulus; and

Fig. 9 is a partial radial section through a bias buff of one type which may embody the present invention.

Referring now to Fig. 1 of the drawings, I have there shown by way of example a portion of a buff similar to that disclosed in the patent to Hall 2,450,793, and embodying a pair of plied annuli 12 of bias fabric set side by side, the two being joined at the inner circumference by a hinge of fabric 14 united to the annuli 12 at that point by the sewing 16 and mounted on a center or hub 18. So far as this figure goes it would illustrate, with such accuracy as to be expected from a drawing of this character, a buff in which the plied annuli 12 were made in accordance with the present invention, which construction is different from that specifically disclosed in the Hall patent referred to. The joining of the annuli by the hinge 14 is convenient, but not essential, to the invention, as they might be halves of a single wider cylindrical band folded up in the middle in the manner well known in the art.

I believe that the invention will be best understood if I describe first the preferred method of manufacture. Referring to Fig. 1, a long web 15 of fabric as it comes in the bolt or similar package, may be laid out on a table. If short pieces of fabric (remnants or mill ends) are to be utilized in the construction, such pieces 17 may be laid on top of the strip 15, and in Fig. 1 we may assume that they are being laid on from left to right, the covering of the strip 15 being as yet incomplete.

These pieces would ordinarily be ends of webs of the same width or somewhat greater width than the strip 15 and of variable lengths, and they may be laid on with the warps of the pieces paralleling the warps of the bottom sheet and one selvage (at the top of the figure) flush with the selvage of the lower piece, the pieces themselves being in abutting relation and of various lengths. Thus, the second piece 17 from the right in the figure is a relatively short piece of the same width as the strip 15, while the one at the right is of greater length and somewhat wider, projecting at the bottom beyond the edge of the strip 15. Such projecting edges are trimmed off at a suitable stage in the process. In some cases the pieces might be of such shape or size that the filling yarns would parallel the warps of web 15. Also while selvages would ordinarily and advantageously be present, the word is herein used primarily as a convenient term of description rather than a word of limitation.

In Fig. 2 a second continuous web 19 is shown applied over the short pieces 17. Such an assemblage of plies is sometimes termed a "book," although that word does not connote any binding. The "book" illustrated and

described is of elementary character. The addition of small pieces and further webs could go on. Various combinations of webs and pieces could be employed. Webs without short pieces could be used alone. However, to permit handling, the bottom ply and the top ply, 15 and 19 in the specific example shown, should ordinarily be continuous webs. Then in the finished article the pieces, if used, form an interior ply or plies.

The completed book of any suitable number of plies is now severed along diagonal lines, such as *ab* and *cd*, to provide sections having the form of an oblique parallelogram as shown in Fig. 3. The angle of these cuts is approximately 45 degrees, but there may be a slight variation in this, in order to facilitate making from a certain width of book a plied annulus of the desired dimension and characteristics. In other words, we cut our pattern to suit our cloth. If the angle is changed from 45 degrees the yarns at the periphery of the buff are not at a true bias position, but a certain amount of variation may be tolerated. The length of the edges *ad* and *cb* is also subject to some variation. It is desirable for economy to make them such that the altitude *ae* will be a multiple of the depth of the plied annuli which are to be produced, for reasons which will be obvious as the description proceeds, and it facilitates matters to make this multiple as large as possible for a single piece. On the other hand the length *ad* should not much exceed the width of the book, that is, the vertical altitude of the parallelogram as shown in Fig. 3, for reasons which will appear. In the drawing it is equal to the width.

In the next step the parallelogram is folded so as to bring the point *b* to the point *a* and the point *d* to the point *c*, producing what is shown in Fig. 4 wherein the letters *a* and *c*, shown in parentheses after the letters *b* and *d*, indicate that the former are underneath. The selvage edges *ad* and *bc* are brought into abutting relation.

The next step is to sew together the edges *ad* and *cb* which may be accomplished by folding the blank as seen in Fig. 4 along the lines of the selvages, so that they may be presented in aligned overlapping relation to the needle *N* of a sewing machine as seen in Fig. 5. A simple straight seam *S* unites the edges. This seam is of an overcast type, permitting the edges to be folded back into abutting relation. When the length *ad* is the same as the width of the fabric, as in the example illustrated, the abutting edges will extend from corner to corner of the folded blank in Fig. 4. If *ad* is shorter they will extend from one corner to an intermediate point of one side and there terminate. However, if the distance is greater they will extend from one corner to an intermediate point of a side, cross its edge and then continue at the back. In that case the sewing of the edges together could not be accomplished so readily and without additional manipulations and possibility of errors.

After the seam *S* is made the blank is returned to the position of Fig. 4 and now appears as shown in Fig. 6, it being in the form of a sleeve open along the ends *bf* and *ed* and consisting of a number of concentric plies, the ends of each of the plies considered severally and the ends of all the plies considered as a unit being joined together in end-abutting relation by the single seam *S*. In Fig. 7 the blank of Fig. 6 is shown opened up into a cylindrical form in order graphically to illustrate its tubular or sleeve-like construction.

The blank of Fig. 6 may cut parallel to its open ends as for instance along the line *gh* in the figure, to provide a multi-ply sleeve of relatively great diameter and small altitude, as is further illustrated in Fig. 8, the width of the severed portion being such as to permit one or more of them to be distorted into an annular form to form a plied annulus 12 in a buff like Fig. 9 or a similar one. The numeral 12 is applied to Fig. 8 to show the relation of the parts in Figs. 8 and 9. If two plied annuli are to be made from a single plied assembly folded at the

center of the buff, the portion cut from the blank of Fig. 6 or 7 would be twice as wide.

It will be clear that where the various short pieces of fabric 17 extend from selvage to selvage of the strips 15 and 17, then no matter how the cuts *ab* and *cd* are made, some portion of each of the short pieces 17 will be secured by the seam *S*. The pieces 17 will form a discontinuous ply between the continuous plies formed by sheets such as 15 and 17, but each separate piece will be anchored by the seam *S*, and in general some portion of each piece within the completed buff will be secured at the center, as by means of the stitching 16 in the example of Fig. 9, independently of whether it is otherwise secured at positions further radially outward. When plied annuli embodying such discontinuous plies in connection with continuous plies are assembled as sections in a complete wheel, either by placing them side by side in parallel planes or by nesting one within another, or both, it is found that no difficulties arise because of the breaks in the continuity occurring in the individual sections.

In forming the book as shown in Figs. 1 and 2, it is very easy to align the edges of the various plies. Subsequent manipulations have little or no tendency to disturb their relative position even when short pieces are used. The single easily applied seam *S* locks all parts together. When a part is cut off its edges are either an original aligned edge or a line of severance. The steps are easy and may be rapidly performed by unskilled labor and result in a product of superior quality.

I am aware that the invention may be embodied in other specific forms without departing from the spirit or essential attributes thereof, and I therefore desire the present embodiment to be considered in all respects as illustrative and not restrictive, as is in fact clear in several matters from the description itself. Reference is to be had to the appended claims to indicate those principles of the invention exemplified by the particular embodiment described and which I desire to secure by Letters Patent.

I claim:

1. A method of making buff sections which comprises superposing a plurality of lengths of fabric with aligning edges, cutting diagonally across the assemblage to sever therefrom an oblique parallelogram, the opposite sides of which corresponding to the original longitudinal edges of the assemblage are not substantially longer than its altitude measured between them but are of a length corresponding to an integral multiple of the radial depth of a predetermined size of buff, folding in corners of the parallelogram to bring said sides into abutting relationship, uniting the abutting edges by a single overcast seam to provide an open-ended multi-ply sleeve with its plies joined against relative movement longitudinal of the sleeve, severing said sleeve into a plurality of ring sections each of a width once or twice the said radial depth and deforming each ring section into an annulus.

2. A method of making buff sections which comprises superposing a plurality of lengths of fabric with aligning edges, cutting diagonally across the assemblage to sever therefrom an oblique parallelogram, the opposite sides of which corresponding to the original longitudinal edges of the assemblage are substantially equal to its altitude measured between them, folding in corners of the parallelogram to bring said sides into abutting relationship, uniting the abutting edges by a single overcast seam to provide an open-ended multi-ply sleeve with its plies joined against relative movement longitudinal of the sleeve, severing said sleeve into a plurality of ring sections each of a width once or twice the said radial depth and deforming each ring section into an annulus.

3. A method of making buff sections which comprises superposing a plurality of lengths of fabric with aligning edges, at least one of said lengths being made up of short pieces set end to end along the longitudinal direction, cutting diagonally across the assemblage to sever therefrom an oblique parallelogram, the opposite sides of

which corresponding to the original longitudinal edges of the assemblage are not substantially longer than its altitude measured between them but are of a length corresponding to an integral multiple of the radial depth of a predetermined size of buff, folding in corners of the parallelogram to bring said sides into abutting relationship, uniting the abutting edges by a single overcast seam to provide an open-ended multi-ply sleeve with its plies joined against relative movement longitudinal of the sleeve, severing said sleeve into a plurality of ring sections each of a width once or twice the said radial depth and deforming each ring section into an annulus.

4. A method of making buff sections which comprises superposing a plurality of lengths of fabric with aligning edges, cutting diagonally across the assemblage to sever therefrom an oblique parallelogram, the opposite sides of which corresponding to the original longitudinal edges of the assemblage are not substantially longer than its altitude measured between them but are of a length corresponding to an integral multiple of the radial depth of a predetermined size of buff, folding in corners of the parallelogram to bring said sides into abutting relationship, again folding the resultant pad along the line of said sides to superpose them for the operation of a sewing mechanism thereon, joining such superposed edges only by a single overcast seam which permits their return to aligned position to provide an open-ended multi-ply sleeve with its plies joined against relative movement longitudinal of the sleeve, severing said sleeve into a plurality of ring sections each of a width once or twice the said radial depth and deforming each ring section into an annulus.

5. A buffing wheel section adapted for assembly with other sections to form a wheel, said section comprising at least one annulus of short axial dimension embodying a multiplicity of fabric plies set side by side and presenting

their yarns angularly to the outer periphery of the annulus, each ply extending through a single circumference between the plies on either side thereof but all the plies being united, each in end-abutting relation, by a single diagonal overcast seam through all the plies at one point in the circumference.

6. A buffing wheel section adapted for assembly with other sections to form a wheel, said section comprising at least one annulus of short axial dimension embodying a multiplicity of fabric plies set side by side and presenting their yarns angularly to the outer periphery of the annulus, at least one interior ply being composed of a series of ring sectors each ply extending through a single circumference between the plies on either side thereof but all the plies being united, each in end-abutting relation, by a single diagonal overcast seam through all the plies at one point in the circumference and each of said sectors having an edge portion thereof secured in said seam.

7. A blank for forming an annular section of a bias buff consisting of a plurality of superposed fabric plies corresponding in shape to an oblique parallelogram, two of the sides of which are bias to the weave of the fabric and two of which are parallel to the direction of one set of yarns, at least certain of the plies being continuous throughout the area of the parallelogram and those last mentioned edges of all the plies being united as compound units in a single overcast seam to provide a multi-ply open-ended sleeve.
